A. L. OPPENHEIM,
PENCIL ATTACHMENT FOR FOUNTAIN PENS,
APPLICATION FILED SEPT. 4, 1917.

1,302,585.

Patented May 6, 1919.

UNITED STATES PATENT OFFICE.

ARNOLD L. OPPENHEIM, OF NEW YORK, N. Y.

PENCIL ATTACHMENT FOR FOUNTAIN-PENS.

1,302,585.

Specification of Letters Patent.

Patented May 6, 1919.

Application filed September 4, 1917. Serial No. 189,514.

To all whom it may concern:

Be it known that I, ARNOLD L. OPPENHEIM, a citizen of the United States of America, residing in the State of New York, city and county of New York, have invented certain new and useful Improvements in Pencil Attachments for Fountain-Pens, of which the following is a full, clear, and exact description.

10 This invention relates to a pencil attachment for fountain pens, being particularly adapted for fountain pens of the compressible sack self filling variety for the reason that leakage of ink through the pencil section is less liable to take place. Aside from the novel combination referred to, certain mechanical features adapting the combination for assemblage are resorted to.

20 I will now proceed to describe my invention in detail, the novel features of which I will point out in the appended claim, reference being had to the accompanying drawing forming part hereof, wherein,

25 Figure 1 illustrates my improved combination in elevation;

Fig. 2 is an enlarged fragmentary longitudinal sectional view;

Fig. 3 is an enlarged detail view of the pencil holding mechanism;

30 Figs. 4 and 5 are cross sectional views on lines 3—3 and 4—4 respectively in Fig. 2; and

35 Fig. 6 is a fragmentary longitudinal sectional view of a modification of my invention.

As herein illustrated, my improvement consists of a barrel 6 in two sections 7 and 8, the section 8 having a pen section 9 at one end thereof and also containing a compressible sack 10 to retain ink. To compress the sack in order to fill same, a lever 11 pivoted at 12 to the section 8, and bearing upon a shoe 13, is utilized. The construction for a self filling fountain pen is well known and needs no further description. As can be seen, the section 7 is reduced at 14, said reduced portion being provided with threads to engage the threads in the open end of the section 8.

40 Within the section 7 I place a pencil holding device 15, consisting of a fixed tube 16 having a spiral slot 17. Within the tube 16 a rotatable tube 18 is located having a longitudinal slot 19. Within the slotted tube

18 a pencil point retaining tube 20 is located 55 having a pin 21 extending through the slot 19 into the spiral slot 17 in the fixed tube 16, the tube or pencil holder is longitudinally movable. To hold the tube 16 stationary I provide a locking device 22 consisting of a 60 corrugated cylindrical block which is secured to a casing 23 which surrounds the tube 16 and which is fastened to same or driven in. To secure the rotatable slotted tube 18 to the rotatable head 28 of the pencil section, I provide same with a corrugated cylindrical block 25 to engage the rotatable head. The head 24 is further provided with a central bore 26 to receive the pencil point retaining tube 20.

70 The rotatable head 24 and tube 20 are held together by the corrugated block 25 which is secured to said tube and forced into the rotatable head. After the head 24 and pencil device 15 are assembled in the manner described, the projecting part of the pencil device will be inserted into the bore 7a of the section 7 and driven in to cause the block 22 to grip the said section 7. The corrugations of the blocks 22 and 25 will be 75 forced into the wall of their respective barrel members and be firmly embedded therein, as shown in Figs. 4 and 5. When the head 24 is rotated, the pencil will be moved to extend from the end of said head for use 80 or contraction into the head. The blocks 22 and 25 are effective means for connecting the pencil holding device and the barrel sections without resorting to rivets or the like.

85 For an ordinary pen, that is a fountain pen that is not a self filler, I plug up one end of the section 7 as shown at 26a Fig. 6, hence there can be no leaking from the ink reservoir through the pencil section. In the form of pen illustrated in Fig. 1, there can 90 be no leakage as the sack contains the ink.

95 What I claim is:

In combination, a pair of tubular sections of uniform diameter, a head fitting frictionally in one of said tubular sections flush 100 with one edge thereof, a tube having one end fitted frictionally within said head and its main body disposed concentrically within said last-named tubular section, a tube longer than the other tube projecting into 105 said other tube and having a flange adapted to engage the inner edge thereof so as to be limited in movement in one direction as-

cordingly, a head frictionally attached upon the projecting end of the longer tube, and engaging the adjacent edge of the first head so as to confine the longer tube against longitudinal displacement, the other tubular section being attached over, so as to rotate together with said longer tube, and means for advancing a pencil point out of the last-

named tubular section when said last-named head and tube are rotated.

Signed at New York city, N. Y., this 30 day of August, 1917.

ARNOLD L. OPPENHEIM.

Witnesses:

EDWARD A. JARVIS.
